Primary Examiner — Janice Patyk*Assistant Examiner* — Kendra L Hebel(74) *Attorney, Agent, or Firm* — McDonnell Boehnen Hulbert & Berghoff LLP(57) **CLAIM**

The ornamental design for a coffee grinder as shown and described.

DESCRIPTION

FIG. 1 is a perspective view of a coffee grinder showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the drawings show portions of the coffee grinder that form no part of the claimed design.
